UNITED STATES PATENT OFFICE.

ALBERT B. HOUSE, OF BROOKLYN, NEW YORK, ASSIGNOR TO INTERNATIONAL MOTOR COMPANY, OF NEW YORK, N. Y., A CORPORATION OF DELAWARE.

GAGE SYSTEM FOR FIRE-ENGINES.

1,316,616.

Specification of Letters Patent. Patented Sept. 23, 1919.

Application filed July 8, 1919. Serial No. 309,489.

To all whom it may concern:

Be it known that I, ALBERT B. HOUSE, a citizen of the United States, residing in the borough of Brooklyn of the city of New York, in the State of New York, have invented certain new and useful Improvements in Gage Systems for Fire-Engines, of which the following is a specification, reference being had to the accompanying drawing, forming a part hereof.

This invention relates to an improved gage system adapted particularly for motor fire engines in accordance with which the gage or gages and their pipe connections with the water lines leading to or from the fire pump are protected against possible freezing by water jackets supplied with warm water from the jacket of the propelling motor. For convenience in this application the gages for both the inlet and outlet sides of the fire pump are shown mounted on a single member provided with separate water chambers therein and the pressure gage on the outlet side of the pump has its water connections jacketed and supplied with warm water from the circulatory system of the propelling motor.

The invention will be described in connection with this embodiment as shown in the accompanying drawing, in which—

Figure 1 is a view in side elevation of a portion of a motor fire engine provided with the improved gage system.

Fig. 2 is a fragmentary view, partly in section and partly in elevation, showing in detail the application of the improved gage system to the water lines of a fire pump.

The motor truck *a* may be propelled by an internal combustion engine *b* and carry a fire pump indicated conventionally at *c*, which may also be driven by the motor *b* in a manner now commonly known. The inlet side of the pump is represented by the connection *d* and the outlet side by the line *e*.

It is desirable to provide one or both of the lines *d*, *e*, with gages *f*, *g*, respectively, for the purpose of permitting the pressures therein to be determined by the attendant. In accordance with the illustrated embodiment these gages *f*, *g* are mounted on a single support *h* chambered as at *i*, *k*, the chamber *i* communicating with the inlet line through a channel *i'* and with the gage *f* through a channel *i''*, and the gage *g* communicating with the outlet line *e* through

a port *k'* and with the gage *g* through a channel *k''*. The port *i''* is normally closed, to cut off communication between the inlet line *d* and the gage *f* by means of a suitable valve, indicated at *l*, but readily operable to subject the gage momentarily to the pressure in the line *d* for a reading. In like manner, the channel *k''* is normally closed by a hand operated valve *m* for the purpose of cutting off communication between the gage *g* and the discharge pipe *e*, but operable to subject the gage momentarily to the pressure in the discharge line *e* for a reading. The discharge line *e* is formed with a port *e'* which communicates with the port *k'* through a pipe *n*. It is the pipe connections of this character which, associated with one or more gages in the fire engine, are subject to freezing. It is the principal object of this invention to protect a connection, such as the connection *n* by means of warm water derived from the circulatory system of the propelling motor *b*. In the illustrated embodiment such a jacket, surrounding the pipe *n*, is indicated by the reference character *o*, and this jacket is connected through the circulatory system of the motor *b* by means of a pipe *p* in which may be disposed a hand valve *p'* to permit the jacket *o* to be shut off from the circulatory system of the motor when warm water is not required in the jacket. In the illustrated embodiment the pipe *p* communicates directly with the jacket of one of the cylinders of the motor *b*, but it is evident that the connection might be effected at any other part of the circulatory system. Drain cocks *n'*, *o'* may be placed at the lower levels of the pipe *n* and the jacket *o*, respectively, to permit all of the water to be drained from the gage system when the latter is not in general use.

The important feature of the invention aside from the particular embodiment illustrated resides in the use of the water in the circulatory system of the motor *b* which is warm for the purpose of protecting one or more of the gages and the connections therefor which might be employed in a motor fire engine.

I claim as my invention:

1. In a motor fire engine, the combination with the motor and circulatory system therefor, fire pump, inlet and discharge pipes therefor, of a gage connected to one of said

105

110

pipes, a jacket for the connection, and a connection between the jacket and the circulatory system.

2. In a motor fire engine, the combination with the motor and circulatory system therefor, fire pump, inlet and discharge pipes therefor, of a gage and chambered support on which the gage is mounted, connections between the chambered support and 10 the gage and between the chambered support and one of said pipes, a jacket for the last named connection and a connection between the jacket and said circulatory system.

3. In a motor fire engine, the combination 15 with the motor and water jacket therefor,

fire pump, inlet and discharge pipes therefor, of a gage and chambered support on which the gage is mounted, connections between the chambered support and the gage and between the chambered support and one 20 of said pipes, a jacket for the last named connection, a connection between the jacket and said first named jacket, and drain cocks in the second named jacket and the connection between the chambered support and 25 said pipe from the fire pump.

This specification signed this 30th day of June, A. D. 1919.

ALBERT B. HOUSE.
